HEAVY OIL CONVERSION WITH LOW COKE FORMATION

Seymour C. Schuman, Titusville, N. J., assignor to Hydrocarbon Research, Inc., New York, N. Y., a corporation of New Jersey

Application November 12, 1953, Serial No. 391,582

10 Claims. (Cl. 208—107)

This invention relates to the conversion of heavy oils into more valuable products, more particularly, the invention is directed to the conversion of hydrocarbon oils boiling above about 700° F. and containing a substantial proportion of asphaltenes.

A principal object of this invention is to convert heavy hydrocarbon oils into valuable gaseous and liquid products with low coke formation. Further objects and advantages will be apparent from the description which follows.

In accordance with the invention, heavy hydrocarbon oil is injected into a high-velocity gaseous stream containing hydrogen and carrying in suspension a heated particulate carrier whereby the oil is converted into volatilized products and a carbonaceous deposit on the carrier. The heavy oils for which the process is particularly adapted may derive from petroleum, coal, tar sands and oil shale and are characterized as boiling essentially above about 700° F. and having a Ramsbottom carbon value (ASTM No. D-524-52T) of at least about 10 and very frequently above 15. Such oils are generally highly aromatic and contain a large proportion of asphaltenes and resinous compounds. To convert heavy oils to lighter liquid and gaseous products with low carbon formation, it has been found necessary to subject the oil in the presence of hydrogen to a temperature in the range of about 1200 to 1600° F., preferably 1300 to 1500° F., for a period not exceeding about 3 seconds, preferably not exceeding about 1 second.

The process employs a finely divided solid carrier, generally of a size that all passes through a 40-mesh sieve and preferably at least about 50% by weight thereof passes through a 100-mesh sieve. The carrier, heated to provide temperatures in the aforesaid conversion range when contacted by the heavy oil, is carried in suspension by a hydrogen-containing gasiform stream traveling at a velocity of at least 10, preferably at least 20, feet per second. Under these conditions, the carrier particles travel with substantially the same velocity of the suspending gasiform stream. Although the carrier particles may in some instances experience a little slippage relative to the gasiform stream, the velocity of the particles will still be at least 70% of that of the gasiform stream.

It is a noteworthy feature of this invention that the conversion of heavy hydrocarbons to more valuable products is carried out at low hydrogen partial pressure and yet the formation of carbon is materially curtailed. Hydrogen partial pressures as low as about 35 p. s. i. (pounds per square inch) are effective in the process of this invention. The hydrogen partial pressure is preferably in the range of 75 to 200 p. s. i. and generally does not exceed 400 p. s. i. The process consumes considerable hydrogen in the conversion of heavy oils; for instance, a consumption of approximately 1000 standard cubic feet of hydrogen per barrel of charge heavy oil is frequently encountered.

The short-time, high-temperature conversion of heavy oils is carried out with the carrier particles dispersed as

2

a dilute phase in the suspending, high-velocity gasiform stream. Generally, the carrier loading does not exceed about 5 pounds per cubic foot of suspending gas and often is in the range of about 1 to 2 pounds per cubic foot.

5 In the course of the hydrocarbon conversion, carbonaceous material is deposited on the carrier particles. The thus fouled carrier, after stripping absorbed heavy hydrocarbons therefrom, is subjected to regeneration. Advantageously, the fouled carrier is reacted with oxygen and steam at temperatures of at least about 1600° F., preferably in the range of 1700 to 2000° F., to yield regeneration product gases containing a substantial proportion of hydrogen. The regenerating gas contains a preponderance of steam and a minor proportion of high-purity oxygen, the latter usually containing at least about 90% by volume of oxygen and preferably at least 95% by volume of oxygen. Steam-to-oxygen volume ratios in the range of 1.5:1 to 5:1 are generally satisfactory for generating the required hydrogen. In many instances, the steam-to-oxygen volume ratio is of the order of 2:1 to 3:1.

The particulate carrier employed in the process of this invention is any solid material that will withstand the desired regeneration conditions, including a temperature above 1600° F., without physically disintegrating or fusing, such as sand, quartz, alumina, magnesia, zircon, beryl or bauxite. Absorptive carriers of the type disclosed in the copending application of C. A. Johnson and S. C. Schuman, Serial No. 388,903, filed October 28, 1953, are preferred.

To describe and explain this invention more fully, reference is made to the accompanying drawings wherein:

Figure 1 diagrammatically illustrates an apparatus adapted for carrying out the process of the invention; and

Figure 2 is a diagrammatic vertical section of a hydrocracker incorporating therein the process of this invention.

40 Referring now to Figure 1, finely divided carrier, all passing through an 80-mesh sieve, heated to a temperature of about 1750° F. in regenerator 10 is passed through slide valve 12 into conversion conduit 14 where it is suspended in a high-velocity gaseous stream containing hydrogen, which is introduced into conduit 14 at the point 16. Into the stream carrying the heated carrier particles through conduit 14 at a velocity of about 25 feet per second, a heavy residuum is injected through feed line 18 and valved branch line 20. Alternatively, the feed stock may be injected into conduit 14 through valved branch line 22 or valved branch line 24 depending upon whether a somewhat shorter or a somewhat longer conversion time is desired. The mixture of feed stock and carrier dispersed in the gaseous stream has a temperature in the range of 1300 to 1500° F. The stream discharges from conduit 14 into cyclone separator 26 where the carrier particles now coated with carbonaceous matter are separated from the gasiform stream containing the cracked hydrocarbons. 45 The fouled carrier particles pass down from cyclone 26 through standpipe 28 into regenerator 10, while the gasiform effluent is withdrawn through outlet 30 and sent to a conventional recovery system which separates the products of conversion into desired fractions.

of about 1750° F. to yield a regeneration product gas rich in hydrogen. While the oxygen is substantially completely reacted in the lower portion of regenerator 10, it is preferred to have a baffle structure 38 disposed at an intermediate level in the fluidized mass of carrier within regenerator 10 so as to curtail top-to-bottom mixing. The upper portion of the fluidized bed which has a pseudo-liquid level 36 provides a zone in which the fouled catalyst discharging from standpipe 28 is subjected to stripping to remove absorbed hydrocarbons from the fouled catalyst. While the regeneration product gases are very effective for stripping absorbed hydrocarbons from the fouled carrier, additional gas, such as steam, may be introduced through distributor 40 particularly where it is desired to maintain a lower temperature in the portion of the fluidized mass above baffle structure 38. Thus, the fouled carrier may be subjected to stripping at a temperature of about 1500° F. above baffle structure 38 and regenerated at a temperature of about 1750° F. below baffle structure 38. The regeneration product gases along with stripped hydrocarbons on emerging from the pseudo-liquid level 36 are withdrawn from regenerator 10 through outlet 42 and passed to a conventional recovery system to separate out the hydrocarbons from the normally gaseous components of that stream.

The suspending gas introduced into conduit 14 at the point 16 may be derived from the gaseous stream leaving regenerator 10 at outlet 42. It is also possible to recycle hydrogen-containing gas which is separated from the gaseous effluent withdrawn at outlet 30.

The apparatus of Figure 2 is essentially a hydrocracker as disclosed in the copending application of J. A. Finnegan, Jr., and F. B. Grosselfinger, Serial No. 299,114, filed July 16, 1952, but modified to include the high-temperature, short-time cracking of a heavy recycle stock in accordance with this invention. Vessel 50 contains a fluidized carrier mass with a pseudo-liquid level 52. The upper portion of the fluidized mass provides a primary cracking zone 54, an intermediate portion containing packing bodies 56 like Raschig rings provides a secondary cracking zone 58 and the lower portion provides a regeneration zone 60. The packing bodies 56 are supported on a perforated plate 62. The charge stock is supplied to zone 54 through distributor 64 while oxygen and steam for regeneration of the carrier particles are introduced through distributor 66. The temperature of primary cracking zone 54 is generally maintained in the range of 850 to 1100° F., preferably in the range of 900 to 1050° F., while regeneration zone 60 is maintained at a temperature of at least 1600° F., preferably in the range of 1700 to 2000° F. Fouled carrier from zone 54 moves down through packed zone 58 countercurrent to regeneration product gases rich in hydrogen and thus is subjected to stripping conditions at increasing temperatures as the carrier approaches zone 60. The carrier stripped of absorbed hydrocarbons discharges from zone 58 into zone 60 where the carbonaceous residue on the carrier particles is gasified by reaction with oxygen and steam.

Regenerated carrier flows from zone 60 through opening 68 into up-transport conduit 70. The flow of carrier through opening 68 may be regulated by the position of valve body 72 mounted on tube 74 which is moved vertically by turning threaded handle 76. The carrier is conveyed up through conduit 70 into zone 54 by a suspending gas introduced through tube 74.

The total reaction effluent comprising the cracked hydrocarbons and the hydrogen-containing regeneration product gases emerges from pseudo-liquid level 52, passes through cyclone separator 78 and flows through outlet 80 to a conventional recovery plant to fractionate the liquid and gaseous products.

Pursuant to this invention, the heaviest hydrocarbon fraction, boiling above 700° F., obtained from the total reaction effluent is recycled for further conversion. This recycle stock is injected through line 82 and nozzle 84

into conduit 70 where it is dispersed in a high-velocity gaseous stream containing hydrogen and conveying regenerated carrier particles. The gas supplied through tube 74 contains sufficient hydrogen to provide in conduit 70 a hydrogen partial pressure in the range of 35 to 400 p. s. i. This hydrogen-containing gas may be obtained by the fractionation of the total gasiform effluent leaving vessel 50 through outlet 80. The recycle stock is thus further converted at temperatures in the range of 1200 to 1600° F. for a period of about 1 to 3 seconds. The conversion products from the recycle stock discharge into the fluidized carrier mass in zone 54 where a substantially lower temperature is maintained; hence, the deep cracking effected in conduit 70 is arrested by the quenching action of the fluidized carrier in zone 54. The amount of recycle stock which is converted in conduit 70 may be varied considerably. It is possible and even commercially attractive to charge a heavy oil to primary cracking zone 54 through distributor 64 and to withdraw from the recovery plant as end products only gasoline and lighter products by recycling to vessel 50 all hydrocarbons boiling above 400° F. In such case, however, it is advisable to fractionate the hydrocarbons boiling above 400° F. into a middle distillate with an approximate boiling range of 400 to 700° F. and a heavy end fraction boiling above about 700° F.; the middle distillate is then recycled in admixture with the charge stock through distributor 64 while the heavy end fraction is recycled through line 82 and nozzle 84.

30 The following examples further illustrate the invention without, however, being intended as limitations thereof:

EXAMPLE 1

An apparatus as illustrated in Figure 1 is charged with 35 bauxite averaging 160-mesh particle size. At an operating gauge pressure of 400 p. s. i., the unit treats 5,000 barrels per day of an asphalt fraction obtained by the propane deasphalting of a 25% by weight Kuwait residuum and having the following characteristics:

40 Specific gravity _____ 1.06
Ramsbottom carbon residue, wt. percent _____ 27
Sulfur, wt. percent _____ 6

The charge stock, preheated to about 550° F., is injected into hydrogen-containing gas flowing through conduit 14 at a rate of about 38 MM s. c. f. d. (million standard cubic feet per day). At the point of oil injection, the combined stream has a temperature of about 1450° F. and this temperature decreases to about 1300° F. when the stream reaches cyclone separator 26. The oil is at conversion conditions for approximately 1 second. The combined gas and oil stream has an average velocity of about 25 feet per second, a hydrogen partial pressure of about 100 p. s. i. and a bauxite loading of about 1.5 pounds per cubic foot of gas.

55 About 3.4 MM s. c. f. d. of oxygen (96% by volume purity) and 6.8 MM s. c. f. d. of steam respectively preheated to 300° F. and 1000° F. enter through conduit 32 to regenerate fouled bauxite at a temperature of about 1850° F. An additional 0.6 MM. s. c. f. d. of steam is supplied through tap 34. Wet steam is introduced through distributor 40 to maintain the fluidized mass above baffle structure 38 at a temperature of about 1500° F.

60 The gasiform effluent from outlet 30 is processed in a recovery plant to separate out gasoline and fuel oil of the quality and in the quantity shown in the first column of Table I. The gaseous residue of the effluent is scrubbed with a suitable solvent, e. g., diethanolamine, to eliminate substantially all of the hydrogen sulfide and carbon dioxide therein, and then contacted in the presence of added steam with an iron-chromium water-gas shift catalyst at a temperature of about 775° F. to transform its carbon monoxide content to carbon dioxide and hydrogen. After removal of water vapor and carbon

dioxide from the shifted gas, the resulting hydrogen-enriched gas contains about 75% by volume of hydrogen, and gaseous hydrocarbons which make up most of the remainder. This gas is recycled to conduit 14 at the rate of 38 MM s. c. f. d. as aforesaid, while an additional 19 MM s. c. f. d. is withdrawn from the system as an end product, namely, a fuel gas of high heating value.

EXAMPLE 2

In a run similar to that of Example 1, air is used in the regenerator in lieu of steam and oxygen and steam

oil product. The third column of Table I gives the quantity and quality of the end products.

EXAMPLE 4

In a run similar to that of Example 3, none of the heavy end fraction is recycled to conduit 70 and steam is used in lieu of hydrogen-containing gas as the transport gas in conduit 70. The conversion products are given in the fourth column of Table I. It is noteworthy that the gasoline yield and quality are inferior to those of Example 3 and the product gas is lower in heating value and quantity.

Table I

Example Design	1 Fig. 1	2 Fig. 1	3 Fig. 2	4 Fig. 2
Transport Gas	H ₂ -Con-taining O ₂ +H ₂ O	Steam	H ₂ -Con-taining O ₂ +H ₂ O	Steam
Regenerating Gas Yields:		Air		O ₂ +H ₂ O
Gasoline, Barrels per Day	1,370	990	14,240	12,950
Fuel Oil, Barrels per Day	945	685	830	4,140
Fuel Gas, MM s. c. f. d.	19.0	59.3	95.5	78.9
Gasoline Quality:				
Octane Number, CFRR Clear	99.2	98.9	90.2	88.0
Sulfur, Wt. percent	0.31	1.70	0.41	0.45
Fuel Oil Quality:				
Gravity, Specific	1.12	1.20	1.22	1.18
Sulfur, Wt. percent	4.7	12.4	8.6	8.0
Fuel Gas Heating Value, B. t. u./s. c. f. (Net)	990	333	500	440

serves as the transport gas in conduit 14. The quality and quantity of the conversion products are shown in the second column of Table I. It should be noted that no only is the yield of liquid products lower than in Example 1 but also the liquid products have much higher sulfur contents.

EXAMPLE 3

An apparatus as illustrated in Figure 2 is charged with the same size bauxite used in Example 1. Operating at a gauge pressure of 400 p. s. i., the unit treats 23,000 barrels per day of a Kuwait residuum having the following characteristics:

Gravity, °API 7.9
Ramsbottom carbon residue, wt. percent 16
Sulfur, wt. percent 4.9

The charge stock is admixed with 23,000 barrels per day of recycled middle distillate obtained from the gasiform effluent leaving vessel 50 through outlet 80. The admixed oils, preheated to a temperature of 550° F., are charged through distributor 64. About 21.9 MM s. c. f. d. of oxygen (96% by volume purity) and 43.8 MM s. c. f. d. of steam respectively preheated to about 300° F. and 1000° F. are used to regenerate fouled carrier at a temperature of about 1850° F. A heavy end fraction recovered from the gasiform effluent exiting at outlet 80 is recycled through line 82 and nozzle 84 at the rate of 8300 barrels per day. Hydrogen-containing gas derived from the gasiform effluent leaving vessel 50 through outlet 80 is passed through conduit 70 at the rate of 84 MM s. c. f. d. and with a velocity of approximately 30 feet per second. The recycled oil is exposed in conduit 70 to a maximum temperature of about 1400° F., a hydrogen partial pressure of 120 p. s. i., a bauxite loading of approximately 2 pounds per cubic foot of gas and a residence time of nearly 1 second. The temperature in the primary cracking zone 54 is 980° F.

The effluent leaving through outlet 80 is fractionated into gasoline, the aforesaid middle distillate (boiling range of 400 to 700° F.) the aforesaid heavy end fraction (boiling above 700° F.) and a gaseous residue. All of the middle distillate is recycled to distributor 64. The heavy end fraction is split into the 8300 barrels per day charged to line 82 and an additional 830 barrels per day which are withdrawn from the system as fuel

30 It is evident from the examples that the process of this invention converts low-value, heavy hydrocarbons into valuable, light products. For stocks of high sulfur content, there is a marked, additional advantage in that the process yields gasoline of relatively low sulfur content. Much of the sulfur in the charge stock is converted to hydrogen sulfide while the hydrocarbons are undergoing conversion.

35 It is clear that the process of the invention is conducted at elevated pressure to maintain the contemplated hydrogen partial pressure. In most instances, operation at a gauge pressure in the range of 150 to 1000 p. s. i. is satisfactory; the preferred range is 250 to 650 p. s. i.

40 In view of the various modifications of the invention which will occur to those skilled in the art upon consideration of the foregoing disclosure without departing from the spirit or scope thereof, only such limitations should be imposed as are indicated by the appended claims.

45 What is claimed is:

1. A process for the conversion of a heavy hydrocarbon oil having a Ramsbottom carbon value of at least about 10, which comprises injecting said oil into a rapidly moving gaseous stream containing hydrogen and having a velocity of at least about 10 feet per second and conveying dispersed heated carrier particles from a regeneration zone hereinafter specified in substantially the same direction as that of said gaseous stream to yield a mixture having a hydrogen partial pressure of at least about 35 p. s. i. and a temperature in the range of about 1200 to 1600° F., maintaining said mixture at temperatures in said range for not more than about 3 seconds, separating said carrier particles from said mixture, recovering converted hydrocarbons from the remaining gaseous portion of said mixture, treating the separated carrier particles in the aforesaid regeneration zone with oxygen and steam at a temperature above about 1600° F. to reheat said separated carrier particles and to gasify carbonaceous material deposited thereon by said oil thereby producing hydrogen-containing gases, recovering from said gases said gaseous stream containing hydrogen, and again conveying the reheated carrier particles from the aforesaid regeneration zone in said gaseous stream containing hydrogen as aforesaid.
2. A process for converting heavy hydrocarbons boiling above about 700° F. and having a Ramsbottom car-

70 75

bon value of at least about 10 to light hydrocarbons boiling below about 400° F., which comprises conveying heated carrier particles from a regeneration zone hereinafter specified by suspension in a gaseous stream containing hydrogen and having a velocity of at least about 10 feet per second so that said carrier particles travel in substantially the same direction as that of said gaseous stream, injecting said heavy hydrocarbons into the suspension of said carrier particles in said gaseous stream to form a mixture having a hydrogen partial pressure in the range of about 75 to 200 p. s. i. and a temperature in the range of about 1300 to 1500° F., maintaining said mixture at temperatures in said range for not more than about 3 seconds, separating said carrier particles from said mixture, recovering said light hydrocarbons from the remaining gaseous portion of said mixture, treating the separated carrier particles in the aforesaid regeneration zone with oxygen and steam at a temperature above about 1600° F. to reheat said separated carrier particles and to gasify carbonaceous material deposited thereon by said oil thereby producing hydrogen-containing gases, recovering from said gases said gaseous stream containing hydrogen, and again conveying the reheated carrier particles from the aforesaid regeneration zone in said gaseous stream containing hydrogen as aforesaid.

3. The process of claim 1 wherein each cubic foot of said gaseous stream containing hydrogen conveys not more than about 5 pounds of said heated carrier particles.

4. The process of claim 1 wherein said carrier particles are bauxite particles.

5. The process of claim 2 wherein each cubic foot of said gaseous stream containing hydrogen conveys not more than about 5 pounds of said heated carrier particles.

6. The process of claim 2 wherein said mixture has a hydrogen partial pressure of at least about 75 p. s. i.

7. A process for converting heavy hydrocarbons boiling above about 700° F. and having a Ramsbottom carbon value of at least about 10 to light hydrocarbons boiling below about 400° F., which comprises conveying heated carrier particles from a regeneration zone hereinafter specified by suspension in a gaseous stream containing hydrogen and having a velocity of at least about

20 feet per second so that said carrier particles travel in substantially the same direction as that of said gaseous stream, injecting said heavy hydrocarbons into the suspension of said carrier particles in said gaseous stream to form a mixture having a hydrogen partial pressure in the range of about 75 to 200 p. s. i. and a temperature in the range of about 1300 to 1500° F., maintaining said mixture at temperatures in said range for not more than about 1 second, separating said carrier particles from said mixture, recovering said light hydrocarbons from the remaining gaseous portion of said mixture, reheating the separated carrier particles in the aforesaid regeneration zone by reacting the carbonaceous material deposited on said carrier particles by said heavy hydrocarbons with oxygen and steam at a temperature in the range of about 1700 to 2000° F. thereby producing hydrogen-containing gases, recovering from said gases said gaseous stream containing hydrogen, and again conveying the reheated carrier particles from the aforesaid regeneration zone in said gaseous stream containing hydrogen as aforesaid.

8. The process of claim 7 wherein the reaction of the carbonaceous material with oxygen and steam is conducted by passing said oxygen and steam upwardly through a mass of said carrier particles with said carbonaceous material deposited thereon under fluidizing conditions.

9. The process of claim 7 wherein each cubic foot of said gaseous stream containing hydrogen conveys not more than about 2 pounds of said heated carrier particles.

10. The process of claim 7 wherein said heavy hydrocarbons have a Ramsbottom carbon value of at least about 15 and a sulfur content of at least about 5% by weight.
